INVENTOR:

UNITED STATES PATENT OFFICE.

JOHN M. JONES, OF WREXHAM, NORTH WALES, ENGLAND.

LEATHER FLUFFING OR GROUNDING MACHINE.

SPECIFICATION forming part of Letters Patent No. 235,249, dated December 7, 1880.
Application filed October 29, 1880. (No model.) Patented in England September 6, 1880.

To all whom it may concern:

Be it known that I, JOHN MEREDITH JONES, a subject of the Queen of Great Britain, and residing at Wrexham, county of Denbigh, 5 North Wales, England, have invented certain Improvements in Fluffing or Grounding Machines, (for which I have made application for a patent in Great Britain, No. 3,610, dated 6th September, 1880,) of which the following is a 10 specification.

My invention relates to machines for grounding or softening skins or leather and producing thereon a nappy or fluffy surface; and it consists in the employment, in combination, of 15 an emery or grinding wheel, a brush-wheel, or similar elastic roller or contrivance with a treadle device, a feed-table, and a fan, all substantially in the manner hereinafter described.

The emery-wheel and brush-wheel or its 20 equivalent are contained within a partially-closed casing, and between them is arranged the feed-table, which is placed at an angle. The brush-wheel or its equivalent is so arranged that it may be brought to exert a 25 greater or less amount of pressure against the emery-wheel by varying the pressure upon the treadle. Provision is made for imparting motion to the emery-wheel, brush-wheel or roller, or similar contrivance, and the fan, the brush- 30 wheel or its equivalent in some cases being caused to rotate or work at a less velocity than that of the emery-wheel. In operating this apparatus, in order to ground down or 35 soften skins or leather and to produce thereon a nappy or fluffy surface, an attendant workman places one or the other upon the feed-table and allows the skin or leather to pass between the surfaces of the brush-wheel or its equivalent and the emery-wheel. At the same time the 40 workman, pressing upon the treadle with his foot, raises the brush-wheel or its equivalent in such a manner as to cause the emery-wheel to abrade or ground away such portions of the 45 surface of the skin or leather as may be necessary. The material removed by the emery-wheel is carried or driven away from the machine by means of the fan.

In order that my said invention may be fully understood, I shall now proceed more particularly to describe the same, and for that purpose shall refer to the several figures on the

annexed sheets of drawings, the same letters of reference indicating corresponding parts in all the figures.

Figure 1 of the accompanying drawings represents a sectional elevation of a machine constructed according to my said invention. Fig. 2 is a sectional plan of the same, and Fig. 3 is an end view, also partly in section.

A is a partially-closed chamber or casing, 55 within which is mounted so as to be capable of revolving an emery-wheel, B, the shaft *a* of the wheel having its bearings in the side cheeks, *b b*, of the chamber. At a suitable distance below the emery-wheel B in the chamber A is arranged a rotatory brush-wheel, C, or similar elastic roller, the shaft *c* of which has its bearings in a treadle-frame, D, mounted on a center, *d*, outside the casing A. By the act of depressing the treadle-lever *D'* of the frame 60 D the brush-wheel or its equivalent may be brought into closer proximity to the emery-wheel, while it is maintained at a suitable distance from the said emery-wheel B by means of a spring, *e*, when the treadle-lever is not 65 acted upon by the attendant. The emery-wheel B slightly protrudes through an opening at *f* in the casing A, and below it, and between it and the brush-wheel or roller C, is an inclined feed-table, E, having an opening at *g* 70 immediately over the said brush-wheel or roller. On this feed-table (which may be covered with sheet-zinc or other smooth substance) is placed, say, for example, a skin to be operated upon, which is caused to pass between the emery-wheel B and the brush-wheel or roller C. The attendant then depresses the treadle-lever *D'*, thus raising the brush-wheel or roller so as to cause the same to press the skin into intimate contact with the emery-wheel B, and, rotatory motion being imparted 75 to the latter and to the brush-wheel or roller C, the skin is ground or softened and a fluffy surface is produced thereon. The material removed by the emery-wheel enters the chamber 80 A through grated openings *h*, and is drawn away from the apparatus by means of an exhaust-fan, F.

Motion may be imparted to the emery-wheel B, brush-wheel or roller C, and fan F in any 85 suitable manner. In the example illustrated motion is communicated from the driving-shaft

G to the emery-wheel B by means of a strap and pulleys, i, and thence to the fan F by means of a strap and pulleys, k, the motion of the brush-wheel or roller C being derived direct from the driving-shaft G through the intervention of a crossed strap and pulleys, l.

The motion of the treadle D', and consequently the degree of pressure applied to the brush-wheel or roller C, may be limited by means of an adjustable screw-stop, m. Doors H are provided in the casing A for access to its interior.

In lieu of using a brush-wheel or elastic roller, brushes mounted on an endless travelling band may be employed. This endless band, with the brushes mounted thereon, may be brought into contact with the emery-wheel by means of a treadle in the manner hereinbe-

fore described with reference to the brush-wheel or elastic roller.

20

I claim as my invention—

The combination of an emery or grinding wheel, a brush-wheel, or an equivalent contrivance, as herein set forth, with a treadle device, a feed-table, and a fan, all substantially as and for the purposes hereinbefore described.

In testimony whereof I have signed my name to this specification in the presence of two subscribing witnesses.

J. M. JONES.
